UNITED STATES PATENT OFFICE.

ROGER JUVET AND ROBERT DE STOUTZ, OF ZURICH, SWITZERLAND, ASSIGNORS TO
THE FIRM OF JUVET, DE STOUTZ & MEYER, OF ZURICH, SWITZERLAND.

EXHIBITION-CAR.

1,397,965.

Specification of Letters Patent. Patented Nov. 22, 1921.

Application filed June 29, 1920. Serial No. 392,806.

To all whom it may concern:

Be it known that we, ROGER JUVET, a citizen of the Republic of Switzerland, residing at Zurich, Belsitostrasse 2, Switzerland, and ROBERT DE STOUTZ, a citizen of the Republic of Switzerland, residing at Zurich, Möhrlistrasse 24, Switzerland, have invented certain new and useful Improvements in Exhibition-Cars; and we do hereby declare 10 the following to be a clear, full, and exact description of the invention, such as will enable others skilled in the art to which it appertains to make and use the same, reference being had to the accompanying drawings, and to letters or figures of reference marked thereon, which form a part of this specification.

The object of the present invention is to provide a car for exhibiting goods and samples without repacking consecutively at different mercantile and industrial centers situated at a distance from each other. By this invention a railway car is arranged as exhibition place and is subdivided into different exhibition-compartments. Further means are provided for adapting the car so as to be suited for a through traffic. An essential feature of the invention is further the provision of a bed in each exhibition compartment whereby a great number of sleeping cars can be dispensed with and the length of the whole train which is only limited by the pulling force of the engine may be used almost entirely for exhibition purposes.

Several exemplifications of the invention are illustrated on the accompanying drawings, in which:

Figure 1 shows a side view partly in section of a car of a first exemplification; 40 Fig. 2 is a plan view of the carriage shown in Fig. 1, its roof being partly removed; Fig. 3 is a section along line A—B of Fig. 1;

Fig. 4 is a side elevation of a second exemplification; 45 Fig. 5 is a horizontal section of Fig. 4;

Fig. 6 illustrates on a larger scale a vertical section through the second exemplification;

Fig. 7 is another vertical section on a smaller scale;

Fig. 8 shows a section along line C—D of Fig. 6;

Fig. 9 is a section along line E—F of Fig. 8;

Fig. 10 shows a detail of Fig. 6;

Fig. 11 is a vertical section through the detail shown in Fig. 10;

Fig. 12 is an enlarged sectional view of Fig. 11;

Fig. 13 illustrates a third constructional example of the invention in a side elevation;

Fig. 14 is a horizontal section of Fig. 13;

Fig. 15 shows a detail of the exemplification shown in Fig. 13 on a larger scale;

Fig. 16 is a modification of Fig. 15.

The cars of the train are subdivided by partition walls 2 into exhibition-compartments 3 which can be singly hired by exhibitors. The partition walls 2 are fixed detachably for instance by means of screws and bolts and each of them can be removed.

It is therefore possible to convert two exhibition-compartments 3 into one compartment. The partition walls 2 are provided with large openings 4 Figs. 1 and 2 closed by means of detachable doors 5. 6 denotes curtains or removable walls enabling one to shut up each compartment separately when the train is running and especially during night time.

In order to maintain the possibility of passing through the cars during those times folding or sliding doors 7 are provided in those parts of the walls which are lying on one side of said closing members 6 and at the front ends of the cars which permit passing through each car in a longitudinal direction and thus along the whole train.

In order to give convenient access to the different compartments during the exhibition the side-wall of the car is subdivided into several hinged members 9. If these members are brought into the position 9^a of Fig. 1, which is done when the car

serves as exhibition-room while standing in the open, their inner surfaces may be used as name-boards or as advertising-boards. In bad weather the hinged members 9 may be brought into the position 9^b shown in Fig.

3 in order to be used as a projecting roof. 100 The roof 10 of the car is provided with skylights 11, which may be protected by means of covers 12. If these covers are lifted, as is shown in Fig. 3, the interior

of the car is illuminated from above. To 105 keep the number of sleeping rooms as low as possible a bed 13 is arranged in each exhibition compartment suspended from the ceiling on straps 14 which are guided over rolls 15. The bed can thus be lowered when 110

required and during other times it is raised to the ceiling.

Preferably such trains may be stationed at larger cities in train sheds and means may be provided to simplify the access to the trains and the passing through all the cars.

In the exemplification of the invention illustrated in Figs. 4-12, the lateral walls 9 of the cars can have lower parts 9^d swung downward and their upper parts 9^e swung upward. The lower parts 9^d are supported by small brackets 14^a pivotally mounted on the car and by the larger brackets 15^a carrying the steps 16. In this position which is shown with dot-dash lines on Fig. 5 they form a kind of veranda used as a gang way, which is provided with detachable railings 17 and to which the steps lead up formed by boards 16 placed on the brackets 15^a. The partition walls 2 of the compartments 3 may again be detached as is shown in Fig. 5 for the compartment 3^a. 18 denotes a cupboard provided in each compartment; boards 19 are stored behind the cupboard which enable in connection with the doors 7 to close each compartment as is shown for the two compartments 3 on the extreme left of the car of Fig. 5. 20 denotes several shelves placed one above the other. In this exemplification the bed 20^a is arranged to one side of the compartment below the shelves, part 21 of the bed serves as a seat during daytime and can be swung up into the position 22. A folding wash-basin 23 is hinged at the cupboard 18 and can be swung out of the latter. The upper parts 9^e of the hinged members are moved upward, act as a projecting roof and when held in this position by means of tie-ropes 24, as is shown in Fig. 7. To enable an entirely dust-proof closing of the hinged members 9^d and 9^e in the position shown in Fig. 6, they are provided with a pneumatic tightening arrangement, which is shown in detail in Figs. 10 to 12. At some of the edges of the hinged members 9^d and 9^e a rubber hose 25 is inserted in such a way that it projects by a small amount above the outer faces. Against this projecting part a facing strip 26 of the other part for instance of 9^e bears and compresses the projecting part of the rubber hose 25 thus producing a pneumatic tightening. The rubber hose of the different hinged members 9^d and 9^e are, by means of connecting pipes 27, in connection with compressed air supply pipes 28. After the hinged members 9^e and 9^d have been shut and bolted in a known manner, compressed air can be forced into the rubber hose 25 by means of an air-compressor and thus a dust-proof tightening of the hinged members is attained.

In the third exemplification of the invention shown in Figs. 13 and 14, instead of the hinged members, wings 29 of folding

doors adapted to turn on vertical hinges are provided, between which there are stationary posts 30, by which the entrance side of the exhibition carriage is supported. The doors 29 are arranged so that they open conveniently into single and double compartments as is shown in Fig. 14. In Fig. 14 all the compartments are shown shut up. In order to arrange for a veranda and a projecting roof, the brackets 15^a are, as is shown in Fig. 15, covered with the boards for the steps 16 and with boards 31. Further there are arranged turnable brackets 32 above the doors on which a tarpaulin 33 is spread, that is rolled up inside the upper part of the carriage when it is not used. As is shown in Fig. 16, instead of the boards 31 corrugated plates 34 or one plate of this kind which extends over the greatest part of the length of the car may be used. The latter plate serves in the lowered position as floor of the veranda and in the upright position, as is shown in Fig. 16, it is lying outside against all the shut doors and acts as a safety device against opening said doors.

This device aims to render the exhibition movable so that it may be adapted in a better way to the requirements of the market in the various industrial branches and in the different consuming centers; in other words it is the exhibition that visits the buyer and not, as has been hitherto the case, the buyer who travels to visit the stationary exhibition. By this invention an intensive exchange of ideas and goods between producer and consumer is rendered possible, which is of the greatest importance in the development of every business.

We claim:

1. In an exhibition car, a plurality of vertical partition walls arranged to divide the car into separate exhibition compartments and forming a continuous interior passage along one side of the car, means for detachably mounting the partitions to permit the formation of exhibition compartments of different size and a bed provided in each compartment.

2. In an exhibition car, a plurality of vertical partition walls arranged to divide the car into separate exhibition compartments and forming a continuous interior passage along one side of the car, means for detachably mounting the partitions to permit the formation of exhibition compartments of different size, a bed in each compartment, and hinged members adapted to be raised and forming part of one side of the car.

3. An exhibition car comprising a railway car subdivisible by detachable walls into exhibition compartments, means to permit a through traffic through the car, a bed provided in each exhibition compartment, and hinged members adapted to be partly raised

and partly lowered and forming part of one side of the car.

4. An exhibition car comprising a railway car, subdivisible by detachable walls into exhibition compartments, means to permit a through traffic through the car; a bed provided in each exhibition compartment, hinged members adapted to be partly raised and partly lowered and forming part of one side of the car, and a pneumatic tightening device actuated by compressed air.

5. An exhibition car comprising a railway car subdivisible by detachable walls, into exhibition compartments, means to permit a through traffic through the car, a bed provided in the exhibition compartment, hinged members forming part of one side of the carriage and adapted to be lowered onto the brackets which can be swung out into the supporting position.

6. An exhibition car comprising a railway

car subdivisible by detachable walls into exhibition compartments, means to permit a through traffic through the car and a bed arranged on one side of the exhibition compartment below a shelf, that part of the bed projecting from under the shelf adapted to be folded in order to serve as a seat during day-time.

7. An exhibition car comprising a railway car, subdivisible by detachable walls into exhibition compartments, means to permit a through traffic through the car, a bed provided in each compartment, and brackets to be swung out from underneath the carriage in order to place a floor for a veranda, and boards for steps on them.

In testimony that we claim the foregoing as our invention, we have signed our names.

ROGER JUVET.
ROBERT DE STOUTZ.
